(57) **CLAIM**

The ornamental design for a cactus decoration with LED lights, as shown and described.

DESCRIPTION

FIG. 1 is a top perspective view of a cactus decoration with LED lights showing my new design.

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion "9" in FIG. 1;

FIG. 10 is an enlarged view of the selected portion "10" in FIG. 2;

FIG. 11 is an enlarged view of the selected portion "11" in FIG. 2; and,

FIG. 12 is an enlarged view of the selected portion "12" in FIG. 3.

Any shading and cross-hatching are not features of the design but are utilized to illustrate the surface contours of the cactus decoration with LED lights design in the drawings. The dash-dot-dash broken line defines the boundary of the enlarged views and form no part of the claimed design.
